(57) **CLAIM**

The ornamental design for an LED module, as shown.

DESCRIPTION

FIG. 1 is a front, left-side, and top isometric view of an LED module showing the new design.

FIG. 2 is a top plan view of the LED module.

FIG. 3 is a right-side elevation view of the LED module.

FIG. 4 is a front elevation view of the LED module.

FIG. 5 is a left-side elevation view of the LED module.

FIG. 6 is a back elevation view of the LED module.

FIG. 7 is a bottom plan view of the LED module.

FIG. 8 is a front, left-side, and top isometric view of a second embodiment of the LED module of FIGS. 1-7.

FIG. 9 is a top plan view of the LED module.

FIG. 10 is a right-side elevation view of the LED module.

FIG. 11 is a front elevation view of the LED module.

FIG. 12 is a left-side elevation view of the LED module.

FIG. 13 is a back elevation view of the LED module; and,

FIG. 14 is a bottom plan view of the LED module.
